PRODUCTION OF COKE AND GAS IN
CHAMBER OVENS

Carl Still, Recklinghausen, Germany

Application February 5, 1931, Serial No. 513,741,
and in Germany February 11, 1930

6 Claims. (Cl. 202—10)

The invention consists in improvements in the production of coke and gas from solid fuel in closed intermittently operated chambers, which are heated through the side walls. The subject of the invention is a process by which the gases and volatile products of distillation can be drawn off by suction from a collecting space provided above the charge and also from the interior of the body of the fuel. By the practice of the process according to the invention, the quality and yield of the coke and also of the volatile products, such as coal gas, tar and hydrocarbons, are improved.

15 The process will be explained applied to a horizontal coke oven.

In the accompanying drawing, which represents an apparatus for carrying out the process according to the invention:

20 Fig. 1 is a vertical section through the centre of a coke oven chamber, of which only a portion including the front end is shown.

Fig. 2 is a vertical cross-section comprising two adjacent oven chambers and two heating walls.

25 In Fig. 2 the chamber on the left is in a condition corresponding to the first stage and the chamber on the right in a condition corresponding in the second stage of the process.

30 The chamber 1 which is heated in the usual manner on both sides by walls 2, and is closed at its front by a door 3, has the usual openings 5 (only one of which is shown) in the roof 4 for introducing the charge of coal and an opening 6 for leading away the gas and is connected by the ascension pipe 7 with a gas and tar main 8. Where the ascension pipe 7 opens into the main 8, a valve 9 is provided in the usual manner and is formed to provide a liquid seal. The framing of the main 8 also carries a gas collecting tube 10 extending over the whole length of the battery. The oven chamber 1 contains the charge of coal to be coked which, in the usual manner, is filled up to a level such that above the surface 11 there is a free gas collecting space 12 in connection with the gas discharge opening 6.

35 In the oven roof 4 there are disposed between the openings 5 and 6 a number, about 8 to 12 or more, of iron boxes 14 inserted over the whole length of the chamber at uniform distances apart, which boxes are closed gas-tight by covers 13 provided with water seals. Fresh sealing water is introduced constantly through connections 15 from pipes 16 disposed on the roof and flows into the boxes 14. Each of the boxes 14

is connected by a side connection 17 with a gas collecting pipe 18 placed in the roof 4 parallel to the longitudinal axis of the chamber, and outside the oven is connected by a by-pass pipe 19 with the gas collecting pipe 10. The lower part of the by-pass pipe 19 is formed to provide a water seal which, when a bell 20 is lowered, shuts off the connection between the pipe 18 and the collecting pipe 10. The sealing water is introduced through a pipe 21.

40 A throttling member 22 in the by-pass pipe 19 by suitable adjustment enables the gaseous pressure in every separate pipe 18 to be regulated: a valve-controlled pipe 23 at the end of the pipe 18 under the by-pass 19 serves to discharge any liquids and condensed vapors entering the pipe 18.

45 In the bottom of each box 14 there is a tubular member 24 projecting upwardly within the box and a downwardly projecting tube 25 of the same diameter, which together guide and hold a concentric pipe 26 disposed in them. After the cover 13 has been removed, the tube 26 can, as required, be inserted or removed. The upper end of the tube 26 projecting into the box 14 carries a bell 27, which, with the casing of the box 14 and its inner tube 24, forms a water seal, by which the interior of the tube 26 is sealed from its external surface. The sealing water is also taken through the connections 15 from the pipe 16, as an overflow of the sealing device of the cover 13, and flows through the side connections 17 into the pipe 18 and, finally, through the discharge pipe 23.

50 The lower end of the tube 26 passes through the gas-collecting space 12 of the oven chamber and extends still further for a distance of about 300 to 500 mm. below the surface 11 of the charge of coal, and is there connected to a tubular duct 28 formed in the body of the coal, which duct extends approximately through the whole depth of the coal in the central portion between the two heated chamber walls. The duct 28 and the tube 26 form a passage for the purpose of drawing off the volatile products of distillation by suction from the interior of the charge of coal.

55 The gases and vapors drawn off enter the collecting box 14 which is closed on all sides and are then led through the connection 17 into the pipe 18 and through the by-pass 19 into the gas collecting tube 10 which is common for the whole battery. The tube 10 and the main 8 are connected separately to different gas suction devices, so that the gaseous pressure in each can

be maintained at a definite value independently of that in the other.

The working of the previously described apparatus in order to carry out the process according to the invention is as follows:—

The oven chambers are constantly heated by the heating walls 2, preferably in the same manner and to the same extent as is usual in the production of coke. The tubes 26 are removed 10 from the oven chamber, as further explained later, before the charge has been finally coked and before the coke has been discharged. After the discharge of the coke, while both doors 3 are closed and the main 8 has been cut off by 15 the apparatus 9, and the pipe 10 by the water sealed bell 20 from the oven chamber, the coal to be coked is charged into the oven chamber in the usual manner and the surface 11 of the coal levelled. The so-called charging gases 20 produced during the coal charging are preferably led away through the ascension pipe 7 by means of any suitable apparatus (not shown).

Then, in order to produce the ducts 28, an iron rod having a pointed end is pushed through 25 the guiding tubes 24, 25 in box 14 vertically into the charge of coal and then afterwards withdrawn. The vertical position of the ducts 28 produced and the symmetrical pressure exerted around them by the charge of coal, ensure that 30 the ducts formed remain intact. The take-off pipes 26 are inserted from above into the boxes 14 so that their lower ends are pressed into the ducts 28 and make a sufficiently tight connection with the latter and after this the covers 13 35 are replaced.

The discharge of the gases driven off during charging, which up to this time have been withdrawn through the ascension pipe 7, is now stopped. The gas is first prevented from entering 40 the main 8, which is shut off by the valve 9 from the oven chamber. The by-pass pipe 19 is then opened by raising the bell 20 and the gas collecting pipe 18 and all the boxes 14 connected thereto are brought into connection 45 with the pipe 10, wherein a relatively slight sub-atmospheric pressure is maintained. In this way, the volatile products of distillation are drawn off by suction through the ducts 28.

An important characteristic of the invention 50 consists in the feature that, during the suction operation, in the ducts 28 and the tubes 26 or, respectively, in the boxes 14 in connection with the latter, a partial vacuum or suction is maintained the degree of which is varied strictly in 55 dependence, as described later, on the progress of the coking within the charge of coal. The necessary regulation for this is effected by suitable and variable adjustment of the throttling member, such as a damper or valve 22 in the 60 by-pass 19.

As an example of the application of the method the treatment of an ordinary coking coal is assumed which during the coking produces well-defined coking seams, that is plastic zones of bituminous composition which form the boundary between the outer part of the charge which has been converted to finished glowing coke and the inner unaltered part. This kind of coal includes according to experience, coals of medium, moderate and small content in volatile constituents; for example, most of the Westphalian coals belong to this class.

In the treatment of this coal, the first stage of the process is introduced directly after the beginning of the operation, by the suction being

adjusted so that the gas pressure in the space 12, when measured by the usual water gauge which is under the influence of the atmosphere on its other end amounts to 0 mm. water gauge, that is to say it is equal to the atmospheric pressure. For this purpose usually a moderate partial vacuum of about 10 to 30 mm. of a water gauge is sufficient in the boxes 14.

After a relatively short time, about one hour, 80 a coking seam 29 is formed in the body of the coal very closely adjacent to the heated walls of the chamber, so that the condition is similar to that represented in the left-hand chamber of Fig. 2. Also, the surface 11 of the coal has been converted, mainly by heat radiated from the arch of the chamber, to a kind of coking seam. Within this coking seam there is a quantity, at first still unaltered and relatively cool, of coal 30, of which the temperature is not substantially higher than 100° C., until the whole of the water content has been driven off, which by experience lasts at least during half of the carbonizing period. Outside the coking seam 29 there is finished, highly glowing, coke 31. As 85 soon as this condition has been set up, and this is an important step and further characteristic of the invention, the partial vacuum, maintained in the ducts 28 of the coal, and which is effective in drawing off the gas, is considerably 90 increased; this reduction of pressure is made 95 possible by the water seal in the boxes 14 and by the apparatus 9. The gaseous pressure in the outer space 12 is maintained, as previously, at 0 mm. of a water gauge. Use is then made 100 of the fact that the whole coking seam forms 105 a nearly tight closure between the inner and outer parts of the body of the coal and allows 110 considerably increased differences of gas pressure to be maintained between these two parts.

The value to which the partial vacuum is to 115 be increased depends essentially on the actual conditions and requirements of the individual cases, which are determined by: The thickness 120 of the coal layers in the horizontal direction from which the charge is to be drawn off, and which, in the first place, depends on the diameter of the chamber; in the second place on the distance between the ducts 28; the packing and 125 granulation of the coal; also, more especially on the rate at which the products of distillation to be drawn off are generated, which again depends on the kind of coal and also on the heating properties of the chamber.

For example, assuming a total carbonizing 130 period of 24 hours, the partial vacuum is increased 135 in the boxes 14 from the above-named very small initial value to, at the end of the first hour, about 50 mm. of a water gauge, and is progressively increased, until at the end of the tenth or twelfth hour, that is approximately 140 at the middle of the carbonizing period, it is approximately from 100 mm. to 150 mm. At the same time, care must be taken that the gaseous pressure in the gas collecting space 12 does not fall substantially below 0 mm.

During this period, the properties of the material and the character of the charge of coal are altered by the advance of the coking seam 145 towards the middle of the chamber, as shown on the right hand chamber of Fig. 2. The body 150 of coke 31 outside the coking seam includes, towards the end of this period of operation, the greater part of the charge; the quantity of the charge of coal 30 which remains unaltered within the coking seam 29 has been reduced to 155

a small proportion of its original quantity. The whole coking seam 29 forms a sort of envelope surrounding the ducts 28. Finally, the coking seams 29 are forced from both sides towards the ducts 28 until they are quite close to the latter, possibly still closer than is shown in the chamber on the right of Fig. 2. The first stage of the process is completed under these conditions.

10 The second stage of the process is introduced by the above-described considerable partial vacuum, for example 150 mm. water gauge or more, prevailing at the end of the first stage, being removed entirely from the boxes 14 or the 15 passages and ducts 26, 28, and the pressure maintained in these parts being made equal to the pressure in the external spaces 12 which is maintained practically equal to that of the external atmosphere, i. e., at 0 mm. of a water 20 gauge as before mentioned. This operating condition is maintained until the coking is completed.

This method of drawing off by suction can be carried out, for example, without withdrawing the tubes 26, since the by-pass passage 19 can be throttled at 22 so much that the effective suction in the gas pipe 18 or in the boxes 14 and in the tubes 26 is practically 0 mm. of a water gauge. It is to be considered, however, that the 30 suction effect, which is consequently considerably weakened in the ducts 28 of the coal, may not be sufficient simultaneously to remove, as previously, also the gases from the outer space 31. It is, therefore, necessary, in order that the 35 gaseous pressure in the gas collecting space 12 should remain at atmospheric or 0 mm. and that no accumulation of gas should here arise, to draw off gases at the same time through the ascension pipe 7 into the main 8. In order to 40 carry out the process more advantageously than in the above described method, at the beginning of the second stage the tubes 26 are removed, so that the ducts 28 are brought into direct connection with the space 12 at the upper surface 11 of the coal, and then all the volatile products 45 of distillation are drawn off uniformly from this common space 12 through the ascension pipe 7 into the main 8. For this purpose the gas stream from the pipes 26 and 18 to the main 10 50 is shut off from the pipe 10 by lowering the bell 20 into the by-pass 19 and the closing device or valve 9 between the ascension pipe 7 and the main 8 is opened.

The described changes which form the essential point of the invention, in the partial vacuum applied to the interior of the coal for drawing off the gases, are justified by the changes taking place in the charge of coal itself and the alterations caused from time to time, thereby in the 55 properties of the distillation products drawn off. At the beginning of the first stage, that is, after the coking seam 29 (shown on the left of Fig. 2) has been formed, the character of the coal 30 within it is essentially unaltered from its original condition on charging, and the paths for the 60 products of distillation flowing from the body of the coal are to a very large extent freed. A moderate suction or sub-atmospheric pressure is, consequently, now sufficient for drawing off the 65 gases from the interior. In the further course of the first stage, tar vapors are continually being condensed by flowing through the cool body of coal and, consequently, the passages for the flow of the products are constantly becoming 70 more choked. Therefore, it is necessary

that the suction should be increased, that is the pressure lowered still further below the atmosphere. This is due to the fact that, towards the end of the first stage, the tar vapors find the greatest resistance to their flow owing to this flow occurring mainly in a narrow zone parallel to the middle plane between two adjacent ducts 28. At this period, however, the largest portion of the bituminous constituents present has been 80 evaporated and drawn off. The further yield of these products is small.

The invention utilizes this fact by stopping the suction from this time onwards from the interior of the charge. The distillation products which from this time are still effectively formed and which are developed from the space enclosed by the coking seams 29 are forced by their own pressure into the ducts 28 and from them led into the space 12 and remain, therefore essentially in the same condition in which they were 85 formed.

At the end of the carbonizing period, when the whole body of coal has been coked, the main 9 8 is cut off from the ascension tube 7 by closing the device 9 and thereby the suction is finally 100 stopped. The doors 3 are opened and removed, and the coke is discharged in the usual manner. Since the tubes 26 have been removed some time before, the coke is discharged without 105 hindrance in the otherwise usual manner.

During the first stage of the process, in which the ducts 28 are connected by the pipes 26 to the pipe 18 and the pipe 10 with this suction from the interior, at least temporarily, the volatile products of distillation developed outside the 110 coking seam 29 can, if required, be drawn off through the ascension pipe 7 and the main 8. In this case, obviously, a gaseous pressure equal to atmospheric must be maintained constantly 115 in the gas collecting space 12.

By this means, two kinds of gases are obtained at the same time, which, since during this process very different suctions are applied for drawing off the gases from the inner and outer spaces, are sharply separated. The gas drawn off from 120 the inner space is a valuable distillation gas with considerable content of benzol vapor of which the heating value at the commencement of the first stage is about 7500 calories per cubic metre; at the end of this stage, about 5500 calories per cubic metre. The gas produced at the beginning of the second stage, which approximates closely to the end of the first stage, has a similar high heating value of 5500 calories per cubic metre and this value is reduced at the end 130 of the second stage to about 3000 calories per cubic metre.

The process described can also be employed with chamber ovens working with a charge of rammed or pressed coal cake. In carrying out 135 the process it is advisable in this case to form the ducts to be provided in the interior of the body of the coal before charging, while still outside the oven chamber, during or directly 140 after the coal cake has been made. After the coal cake has been introduced into the oven chamber, the tubes 26 are inserted from the oven roof in the manner previously described, so that their lower ends extend into the ducts so formed. 145 The operation is carried out in other respects in the same manner as in the above example; only on account of the usual greater density of the coal cake a higher vacuum must be employed in drawing off the gases from the ducts.

The following advantages are obtained by the process according to the invention:—

(1) In the production of a valuable metallurgical coke essentially improved by-products are obtained, more particularly a valuable tar with rich content in benzene and thin clear oils with little pitch and scarcely any naphthalene.

(2) The transference of heat from the heating walls to the charge of coal is very much improved on account of the strong flow of gases through the charge due to the high partial vacuum, so that the carbonizing period is considerably reduced, by a quarter to a third.

(3) Since a considerable proportion of all the distillation gases and volatile matters produced at low temperature are led away from the ducts externally, less heat is required for heating the oven and also less work required in the gas condensing plant and smaller plants can be used for this purpose.

(4) The high partial vacuum is maintained in the ducts 28 for that portion of the carbonizing period during which only cool gases and vapors traverse the tubes 26, and this fact together with the possibility that these tubes can be removed before the end of the carbonizing period ensures that the said tubes and the take-off pipes connected with them are not injured by the operation and simplifies the carrying out of the process.

What I claim is:

1. The process for the production of coke and gas in intermittently operated externally heated oven chambers containing a charge of coal and provided with a gas collecting space above the surface of the charge and with interior ducts, which comprises drawing volatile distillation products separately from the interior of the body of the coal and from the gas collecting space, constantly maintaining the gas pressure in the collecting space approximately equal to that of the atmosphere and gradually reducing the pressure in the ducts of the charge from the start of the coking process to at least 100 mm. of a water gauge below atmospheric pressure.

2. The process for the production of coke and gas in intermittently operated externally heated oven chambers containing a charge of coal and provided with gas collecting space above the surface of the charge and with interior ducts, which comprises withdrawing volatile distillation products separately from the interior of the body of the coal and from the gas collecting space, constantly maintaining the gas pressure in the gas collecting space approximately equal to that of the atmosphere and gradually reducing the pressure in the body of the charge from the start of the coking process to at least 100 mm. of a water gauge below atmospheric pressure, and finally near the end of the coking process raising said pressure to substantially zero mm.

3. The process for the production of coke and gas in intermittently operated externally heated oven chambers containing a charge of coal and provided with a gas collecting space above the surface of the charge and with interior ducts, which consists in forming vertical ducts in the interior of the body of the coal, withdrawing

separately the volatile distillation products from the gas collecting space and from the ducts in the interior of the charge, maintaining pressure in the gas collecting space approximately equal to that of the atmosphere and adjusting pressure in the ducts whereby at the start of the coking, it is moderately sub-atmospheric, reducing said pressure to at least 100 mm. of a water gauge below atmospheric during the further course of the coking process, and raising said pressure in said ducts to substantially atmospheric before the end of the coking process.

4. The process for the production of coke and gas in intermittently operated externally heated oven chambers containing a charge of coal and provided with a gas collecting space above the surface of the charge and with interior ducts, which consists in forming vertical ducts in the interior of the body of the coal, withdrawing separately the volatile distillation products from the gas collecting space and from the ducts in the interior of the charge, maintaining pressure in the gas collecting space approximately equal to that of the atmosphere and adjusting pressure in the ducts whereby at the start of the coking it is moderately sub-atmospheric and in the further course of the coking process is reduced to at least 100 mm. of a water gauge below atmospheric.

5. The process of producing coke and gas in intermittently operated externally heated oven chambers containing a charge of coal and provided with a gas collecting space above the surface of the charge and with interior ducts, which consists in withdrawing separately the volatile distillation products from the gas collecting space and from the interior of the charge by suction, forming coking seams which gradually approach each other from the heated side walls of the oven, maintaining pressure in the gas collecting space at approximately atmospheric, gradually reducing the pressure in the interior ducts of the charge from a minimum below atmospheric pressure at the start of the coking process to approximately 100 mm. of a water gauge below atmospheric until the coking seams approach the center of the charge, then connecting the interior of the charge with the gas collecting space and reducing the pressure in the interior to substantially 0 mm. of a water gauge.

6. The process of withdrawing distillation products of different volatility from a charge of coal in a horizontal, externally heated chamber oven, which comprises charging coal loosely into said chamber, leaving a gas collecting space between the surface of the charge and the oven roof, forming vertical ducts in the charge, withdrawing volatile distillation products separately from the interior of the body of the charge through said ducts and from the gas collecting space above the charge, constantly maintaining the pressure in the gas collecting space substantially equal to that of the atmosphere throughout the coking period, and applying progressively increasing suction below atmospheric pressure to said ducts as the coking process progresses throughout the coking period.
